JOINT FOR CONCRETE PAVEMENTS AND
THE LIKE

Clifford Older, Wilmette, Ill.

Original application September 26, 1931, Serial
No. 565,229. Divided and this application Jan-
uary 6, 1934, Serial No. 705,578

9 Claims. (Cl. 94—17)

The present application is a divisional application of my parent application, Serial No. 565,229, filed September 26, 1931, on Expansion joints for concrete pavements and the like, and is particularly concerned with the modifications of the expansion joints which are arranged for initial contraction of the adjacent concrete, rather than initial expansion, although the joints are also adapted to take care of expansion which occurs subsequently to the initial contraction.

In view of the fact that "expansion joints," as they are called in the trade, also permit contraction; and "contraction joints," so-called, also permit expansion after their initial contraction; and the fact that the features of this invention may be used in either the so-called contraction or expansion joints, I use the terms "expansion joints" and "contraction joints" synonymously to cover either one, except where the context, functions, or structures indicate a distinction.

In the expansion joints of the prior art, the cracks appearing between the sections of pavement are ordinarily filled with a plastic or semi-plastic material, such as asphalt or tar. When such joints close, due to the expansion of the adjacent concrete sections, all, or nearly all, of the plastic material is forced out at the top of the joint, since it is prevented from being forced out below the concrete by the presence of the subgrade material. The plastic material which is forced out at the top of the joint forms, at least temporarily, ridges of material across the pavement, which are struck by the wheels of the passing vehicles, causing an impact blow to fall upon the adjacent concrete slabs.

Ultimately, the ridges of semi-plastic material may be flattened out by traffic, but in the meantime the pavement may be seriously damaged. If the plastic filler is soft enough so that it will flatten out immediately under traffic, it will also flow sidewise due to the crown of the pavement, and leave the center only partially filled, and the surplus flows over the surface of the pavement, forming unsightly pools.

It is also desirable that an expansion joint should permit widening of the joint or crack from its initial position and rewidening from any predetermined position, in order to take care of expansion in the summer and contraction of the concrete pavement sections in the winter. When a joint is filled with such plastic material, it cannot fulfill these functions, because the material which is forced out by the closing of the expansion joint crack is flattened out, and the joint must be refilled with plastic every time it opens,

which is a nightly occurrence, if the joint is to be kept free from sand and other material.

One of the objects of the present invention is the provision of an improved expansion joint, in which no plastic or compressible filler is required.

Another object is the provision of an improved expansion joint which is capable of permitting either expansion or contraction of the concrete sections, and permitting a substantial widening or closing of the crack or space between the sections without exposing any opening into which soil or other foreign material may enter and interfere with future effective operation of the joint.

Another object is the provision of an improved expansion joint construction, by means of which each section of concrete is supported and reinforced by the adjacent sections so as to eliminate the undue strains which would otherwise be imposed upon the concrete sections at their edges.

Another object is the provision of an improved sliding construction for an expansion joint, which is adapted to automatically maintain itself in clean and operative condition by virtue of its own operation, and which positively precludes the entrance of any dirt or foreign material between the adjacent sections of concrete.

Another object is the provision of an improved expansion joint assembly which is adapted to maintain the adjacent concrete sections in horizontal alignment to eliminate any possibility of one section settling below the other, or producing any bump or irregularity in the pavement at the joint.

Another object is the provision of an improved expansion joint assembly which may be manufactured out of standard structural shapes and plates, or which lends itself readily to manufacture out of sheet metal, so that the metallic members may be manufactured at a low cost.

Another object is the provision of an improved method of constructing expansion joints by means of which a good bond is assured between the parts of the expansion joint and the concrete section, and the shrinking away of the concrete section from the expansion joint during the drying of the concrete is eliminated.

Other objects and advantages of the invention will appear from the following description and from the accompanying drawing, in which similar characters of reference indicate similar parts throughout the several views.

Referring to the single sheet of drawings accompanying this specification,

- Fig. 1 is a vertical sectional view through a concrete pavement equipped with a simplified form of fitting adapted to be used as a contraction joint;
- 5 Fig. 2 is a side elevational view of the fastening clip used in Fig. 1, with the tie bar in section on the plane of the line 2—2 of Fig. 1;
- Fig. 3 is a view similar to Fig. 1 of another and more simple form of contraction joint;
- 10 Fig. 4 is a view of the same contraction joint of Fig. 3, with the parts in the position which they assume when the concrete sections have contracted;
- Fig. 5 is a view similar to Fig. 1 of the same 15 expansion joint, the section being taken on a plane corresponding to the line 5—5 of Fig. 6;
- Fig. 6 is a side elevational view of the fitting employed in Fig. 5;
- Fig. 7 is a horizontal sectional view taken 20 through the ends of two adjacent fittings of the type shown in Fig. 6, for the purpose of illustrating the mode of joining sections of the fittings together.
- Fig. 8 is a fragmentary sectional view of the 25 bottom of an expansion joint, taken from the parent application, for the purpose of illustrating the application of the invention to another embodiment, such as an expansion joint.
- The embodiment which has been chosen to 30 illustrate the invention consists of the concrete pavement, such as a roadway, the cross section of which, longitudinally of the road or transversely to the road, may be substantially as shown in Fig. 1.
- 35 The present contraction joints may be located as often as desired, and a plurality of contraction joints are usually located at regularly spaced intervals between the expansion joints which are employed at greater intervals or greater distances from each other. The fittings which are 40 employed to make the present expansion joint units are preferably built up of standard angle iron members and metal plates in order to construct the devices most economically and to provide for the closing of apertures which are left, by striking out anchoring formations and attaching flanges. In some embodiments of the invention, however, the fittings may be made up of sheet metal, such as steel, which is stamped 45 or bent to the configuration shown in Fig. 1. The angle irons are preferably made of rust-resisting or stainless steel, so as to eliminate any possibility of the joints sticking or becoming rusted together.
- 50 It should be understood that all of the advantageous features described herein need not be employed in every embodiment of the invention, but any of the features described in the various modifications may be employed in any other modification that is adapted to the use of such a feature.
- 55 Referring to Figs. 3 and 4, this is a sectional view of an extremely simple form of sliding seal and parting strip which is adapted to be used as a joint protector or as a traffic line marker. When used as a traffic line marker, the fitting of Figs. 3 and 4 will, of course, extend in the direction of traffic, and it may be used for marking the lanes of vehicular traffic longitudinally of 60 the pavement, or for marking the transverse lanes of pedestrian traffic, or islands of safety.
- In the installations of Figs. 3 and 4, the adjacent sections of concrete 81, 82 have their upper edges or corners protected by the fitting 83. The 65 fitting 83 preferably comprises a metal member of substantially T-shape in cross-section, having a pair of horizontally extending flanges 84, 85, and a vertically extending flange 86. The vertically extending flange 86 has a plurality of lugs 87 struck out of the body of the flange and extending in a horizontal direction into the body of one concrete section 82 for the purpose of anchoring the fitting to one section.
- The fitting 83 is pressed into the concrete while it is green, and the concrete is finished flush with the upper flanges 84, 85. As the concrete sets, the crack 88 is formed due to the weakening action of the vertical flange 86, and the fitting 83 is anchored to the section 82 by the lugs 87. Lugs 87 may be provided with any form of anchoring formation 89. The flange 84 is adapted to slide with respect to the surface 90 of the section 81, and to prevent foreign material from entering the top of the crack 88.
- Fig. 4 illustrates the position of the parts when some contraction has taken place in the adjacent sections of concrete 81, 82. It will be noted that the present contraction joint enables the section 81 to support the section 82 in a vertical plane, but it does not enable the section 82 to extend any support to the section 81, and it does not positively prevent all relative vertical movement between the two sections.
- Fig. 5 illustrates a similar view of another modification in which fittings 83 have been utilized on both the top and the bottom of the concrete. The vertical flanges 86 are joined by a multiplicity of relatively narrow metal plates 91, 92, 93, which are secured to the flanges by spot welds or rivets 94. In this embodiment, the fitting seals the crack both at the bottom and the top of the concrete, and prevents relative vertical movement between the two adjacent sections, but the sliding movement takes place between the metal fitting and the concrete surfaces 98 of the adjacent section.
- It is not necessary to use continuous plates extending from one end to the other of a fitting of the type of Fig. 5, since there is no chamber formed between the adjacent sections of the concrete, and the fitting is intended to provide only for initial contraction. The space 95 between the metal straps 91—93 may be filled with concrete, but a crack appears at these points by reason of the weakening which is produced in the concrete by the vertical flanges 86 and straps 91—93.
- It is also possible to make the fittings of Figs. 5 and 6 in relatively short sections, and to secure them together by a sliding fit. For this purpose, the strap 91 has its left edge 96 projecting beyond the end of the fitting 83 to serve as a male joint member. The metal strap 93 is provided with an offset portion 97 to space the flange 86 from the vertical flange 86 a distance which is equal to the thickness of a strap 91.
- The end 96 of the fitting at the right of Fig. 7 will then fit into the crack 88 in the fitting at the left of Fig. 7 between the flanges 86 and 86, thereby joining these sections 100 and 101 together and maintaining alignment between the sections 65 until the concrete has become set.
- Referring to Figs. 1 and 2, these are illustrations of one mode of supporting the fittings of Figs. 5 and 6 in proper position during the construction of the concrete pavement. The elongated U-shaped member 102 comprises a rod which is provided with a pair of downwardly extending points 103, 104. The points 103, 104 may be driven into the ground adjacent the desired location for a contraction joint or a traffic 70 75

marker, and a place will be easily found for driving these points in spite of the presence of stones or other difficulties, for the reason that it is not necessary to locate the member 102 at any exact point. The member 102 need only be located approximately near the location of the desired traffic marker or contraction joint, for the reason that the fitting is adjustably mounted on the member 102.

10 The fitting illustrated in Fig. 1 for the contraction joint may be substantially as shown in Fig. 5, in which case it will be provided with the intermediate spaces 95 of Fig. 6 between the straps 91, 92, 93. The clip 105 comprises a strip of metal 15 having a slot 106, 107 in each end for slidably receiving the vertical flanges 86 of the fittings 83. At one or both sides, the clip 105 is provided with a laterally projecting portion having a pair of resilient fingers 108, 109 adapted to be bent about 20 the rod 102. The fingers 108, 109 may either be resilient for engaging the rod 102 resiliently, or they may be clamped about the rod 102 by pressing the fingers together about the rod.

It will be evident that when the clip 105 and 25 tie bar 102 are assembled together, the clip 105 may be rotated to the dotted line position of Fig. 2 and inserted in any of the spaces 95 in the contraction joint fitting. The clip is then rotated to a vertical position, as shown in full lines in 30 Fig. 2, the flanges 86 engaging in slots 106, 107. The contraction joint fitting may then be located in any desired position, since the fingers 108, 109 will permit the sliding of the clip on the tie bar 102. The tie bar 102 also serves to prevent relative vertical movement between the two sections 35 of concrete 81, 82.

In some embodiments of the invention, such as, for instance, where the fitting is used for a traffic 40 marker, the complete tie bar is not required, and the member 102 may be cut off at the point 110, only half a tie bar being used for providing an adjustable support.

Referring to Fig. 8, this is a fragmentary view 45 of the bottom of an expansion joint embodying my invention, taken from the parent application. In this embodiment, 83 indicates a lower upper load transmitting member made of an angle iron, and acting in the same way as those previously described. The angle iron has the vertical flange 86, which is disposed at the crack between the 50 concrete sections 81, 82, and it has the horizontal flange 84 extending in the same direction as an engaging surface on the opposite concrete section 81. The load transmitting member 83 is anchored in the concrete section 82 by anchoring lugs 87, and therefore it acts in the same way as the 55 embodiment described in Figs. 1-7, except that the joint of Fig. 8 is adapted for initial expansion, and may be termed an expansion joint. It differs in that an additional angle iron 26 is used on the adjacent lower corner of the concrete section 81. This additional angle iron 26 has anchoring lugs 43, a vertical flange 21, and a horizontal flange 51. Its vertical flange 21 is spaced from 60 the vertical flange 86 on the angle iron 83, thereby leaving an expansion space 22. In this case the engaging surface on the concrete section 81, which is engaged by the flange 84 of angle iron 83, is the bottom of the flange 51. It will be seen 65 that the action of the load transmitting member 83 is exactly the same except that it is adapted to slide more readily, due to the fact that the surface of the concrete is covered with metal 51 at the point of sliding engagement.

70 The pin 57 merely holds the parts of such a

joint together as a unit when the joint is being installed, and after the concrete is hard, the pin is withdrawn, forcing its bent end 68 to straighten out.

It is further requested that an additional figure, 5 Fig. 8, be added to the drawing of this application, by the draftsman, as shown in the attached sketch in red ink on a photocopy of the drawing, which also shows its location at the bottom. Approval by the examiner of the attached draftsman's letter with the sketch is solicited.

It will thus be observed that the present invention is capable of being embodied in a number of more simple forms of construction, and while these simpler forms of construction do not 15 have all of the advantages of the preferred form of embodiment, they are capable of performing new and useful results and do not require the use of any semi-plastic filler.

It will thus be observed that in the contraction 20 joint proposed it is not necessary to use any plastic or so-called compressible filler. The joint may either widen or close, after initial contraction of the concrete, a substantial predetermined amount without exposing any opening into which soil or 25 other foreign material may enter to prevent the future functioning of the joint.

The overlapping, sliding steel members which 30 prevent the entry of soil are so tightly fitted together in construction, and are designed of such strength that no relative vertical movement can take place between the adjacent slabs. A vertical force exerted upon one slab is immediately transmitted to the adjacent slab, and thus both concrete sections serve immediately to 35 support a load that may come upon one slab only. The elimination of the causes of impact at the 40 joints, and the provision for material support by the adjacent sections effects an economy in the design of the whole pavement, since it is not necessary to make the slabs as thick as would otherwise be necessary.

The present contraction joint permits the use 45 of standard structural shapes and plates or members which are made entirely of sheet metal. The complete contraction joint unit is capable of being constructed as a unit in the factory and capable of being handled or shipped in a single piece like a box girder. The troubles which are caused by the use of semi-plastic fillers for contraction 50 joints are entirely eliminated by the present contraction joint, and the present device is capable of giving long service under the most adverse 55 conditions without necessity for repair or attention of any kind.

While I have illustrated a preferred embodiment of my invention, many modifications may be made without departing from the spirit of the invention, and I do not wish to be limited to the precise details of construction set forth, but desire to avail myself of all changes within the 60 scope of the appended claims.

Having thus described my invention, what I 65 claim is new and desire to secure by Letters Patent of the United States, is:

1. An expansion joint unit for concrete pavement comprising a pair of metal members of substantially T-shaped cross section, the upper flanges of the T's being arranged substantially flush with the upper and lower surfaces of the 70 concrete pavement, and the vertical flange of the T section having a multiplicity of anchoring lugs struck out of said flanges and bent out transversely to the length of said metal members, and a plurality of spaced metal plates connected to 75

said vertical flanges at intervals for maintaining said metal members in spaced relation to each other, the spacing of the upper flanges of the T being substantially equal to the thickness of the 5 concrete.

2. In a concrete pavement, the combination of a pair of sections of concrete located adjacent to each other, with a contraction joint member comprising a stock metal bar of substantially T shape, said bar having an elongated flange at the top of the T arranged substantially flush with the surface of the concrete and having the flange corresponding to the stem of the T arranged at the juncture between the sections 10 of concrete, and a plurality of anchoring formations struck out of the latter flange and embedded in one of the sections of concrete, whereby said bar is carried by one of the sections of concrete and slidably engages the upper surface of the other section of concrete to maintain the two sections in substantial alignment, and a similar bar arranged at the bottom of the concrete and having its anchoring formations secured in the same section, and a plurality of metallic members extending from the flange of one bar to the 15 other bar and fixedly secured to both bars to hold said bars in spaced relation to each other.

3. In a concrete pavement, the combination of a pair of sections of concrete located adjacent 20 to each other, with a contraction joint member comprising a stock metal bar of substantially T shape, said bar having an elongated flange at the top of the T arranged substantially flush with the surface of the concrete and having the flange corresponding to the stem of the T arranged at the juncture between the sections 25 of concrete, and a plurality of anchoring formations struck out of the latter flange and embedded in one of the sections of concrete, whereby said bar is carried by one of the sections of concrete and slidably engages the upper surface of the other section of concrete to maintain the two sections in substantial alignment, and a similar bar arranged at the bottom of the concrete and having its anchoring formations secured in the same section, and a plurality of metallic members extending from the flange of one bar to the 30 other bar and fixedly secured to both bars to hold said bars in spaced relation to each other, 35 said bars being supported by a plurality of notched clips, said clips being carried by a horizontal anchoring rod having downwardly extending points driven into the sub-soil.

4. In a concrete pavement or the like, the combination of a pair of adjacent sections of concrete 40 pavement with a metallic joint connecting device comprising a stock metal member having a vertically extending flange extending into the concrete vertically to a sufficient distance to weaken the concrete and produce a crack in substantial alignment with said vertically extending flange, said metallic member having a horizontally extending flange extending at substantially right angles to the vertically extending flange and located substantially flush with the surface of the concrete, said horizontally extending flange slidably engaging one of the sections of concrete pavement and said vertically extending flange having a plurality of integral laterally projecting lugs provided with anchoring formations and extending into and embedded in the other section of concrete pavement, whereby said metallic member is fixedly secured to said other section of concrete pavement and slidably engages the first- 45 mentioned section of concrete pavement to trans-

mit load from said other section to the first-mentioned section of concrete by means of said horizontally extending flange engaging the upper surface of the concrete pavement, another similar metallic member located at the bottom of the 5 concrete pavement and similarly arranged with respect to said sections of concrete, and a plurality of vertically extending bars secured to said vertically extending flanges and holding said metallic members in spaced relation to each 10 other, the spacing being substantially equal to the thickness of the concrete.

5. In a concrete pavement or the like, the combination of a pair of adjacent sections of concrete pavement with a metallic joint connecting device comprising a stock metal member having a vertically extending flange extending into the concrete vertically to a sufficient distance to weaken the concrete and produce a crack in substantial alignment with said vertically extending 15 flange, said metallic member having a horizontally extending flange extending at substantially right angles to the vertically extending flange and located substantially flush with the surface of the concrete, said horizontally extending flange slidably engaging one of the sections of concrete pavement and said vertically extending flange having a plurality of integral laterally projecting lugs provided with anchoring formations and extending into and embedded in the 20 other section of concrete pavement, whereby said metallic member is fixedly secured to said other section of concrete pavement and slidably engages the first-mentioned section of concrete pavement to transmit load from said other section 25 to the first-mentioned section of concrete by means of said horizontally extending flange engaging the upper surface of the concrete pavement, another similar metallic member located at the bottom of the concrete pavement and similarly arranged with respect to said sections of concrete, and a plurality of vertically extending bars secured to said vertically extending flanges and holding said metallic members in spaced relation to each other, the spacing being substantially equal to the thickness of the concrete, a plurality of double-pointed members driven into the sub-soil for supporting said metallic members, and a clip having slots for engaging said vertical flanges, said clip being removably secured upon said members and said clip being rotatable upon the members.

6. A road joint former comprising bottom and top sealing members, upright supporting bars secured on the bottom sealing member for holding the top sealing member in position, and load transmission anchoring means on the top sealing member to hold the same against removal when embedded in concrete and furthermore serving to transmit loads from one concrete road 55 slab to another.

7. In a joint for concrete structures, the combination of a pair of adjacent sections of concrete, said sections having a crack formed between them at their juncture with a load transmitting member having a flange extending in the general direction of the crack between the sections and located substantially at said crack, said load transmitting member having integral anchoring lugs formed out of said flange and having a load transmitting flange extending substantially in the same direction as an engaging surface carried by one of the concrete sections, said latter flange being located for sliding engagement with said engaging surface carried by said 70 75

concrete section and the anchoring lugs extending oppositely from said first flange and being fixedly embedded in the other concrete section whereby loads on the one concrete section are transmitted through said flange and load transmitting member to the other concrete section to maintain alignment of said sections.

8. In a joint for concrete structures, the combination of a pair of adjacent sections of concrete, said sections having a crack formed between them at their juncture with a load transmitting member having a flange extending in the general direction of the crack between the sections and located substantially at said crack, said 10 load transmitting member having integral anchoring lugs formed out of said flange and having a load transmitting flange extending substantially in the same direction as an engaging surface carried by one of the concrete sections, said 15 latter flange being located for sliding engagement with said engaging surface carried by said section and the anchoring lugs extending oppo-

sitely from said first flange and being fixedly embedded in the other concrete section whereby loads on the one concrete section are transmitted through said flanges and load transmitting member to the other concrete section to maintain 5 alignment of said sections, and a second similar load transmitting member carried by one of said concrete sections and slidably engaging another of said sections to transmit load from one section to another in a direction opposite to the 10 transmission effected by the first mentioned load transmitting member.

9. A road joint former comprising bottom and top sealing members, upright supporting means secured on the bottom sealing member for holding the top sealing member in position, and load transmission anchoring means on one of said sealing members to hold the same against removal when embedded in concrete and furthermore serving to transmit loads from one concrete 15 road slab to another.
